SHIPPING AND DISPLAY CONTAINER
FOR JEWELRYWilliam J. Thompson, Edgewood, R. I., assignor
to C. & M. Manufacturing Co., a corporation of
Rhode Island

Application November 27, 1948, Serial No. 62,345

4 Claims. (Cl. 206—75)

1

The present invention relates to shipping and display containers and has particular reference to containers for jewelry items such as bracelets and the like.

The principal object of the invention is to provide a jewelry article container which includes a one piece rim element and an article support card adapted to be readily locked therein.

Another object is to provide a rim element for an article container which may be readily molded in one piece.

A further object of the invention is to provide a container rim and an article support element which may be quickly assembled and locked together against relative movement.

With the above and other objects and advantageous features in view, the invention consists of a novel arrangement of parts more fully disclosed in the detailed description following, in conjunction with the accompanying drawings, and more specifically defined in the claims appended thereto.

In the drawings,

Fig. 1 is a perspective view of an illustrative container embodying the invention;

Fig. 2 is an enlarged bottom plan view thereof, the article support element being removed;

Fig. 3 is a vertical section on the line 3—3 of Fig. 2, the article support element being in position;

Fig. 4 is a section on the line 4—4 of Fig. 3; and

Fig. 5 is an enlarged perspective bottom detail showing the tab and slot lock for the article support element.

It has been found desirable to provide a shipping and display container which is ornamental, and is inexpensive to manufacture and assemble. To this end, I provide a container rim of special form which may be pressed out of metal but preferably is molded from plastic material, and I mount an article support element in the container rim so as to be securely held therein, said support element being of thin material and preferably of cardboard, and covered if desired with plush fluff or the like.

Referring to the drawings, the container 10 includes an ornamental rim 11, which is preferably molded of plastic material, and an article support or holder 12, which is preferably of cardboard and which may if desired have its upper surface covered with plush fluff or ornamental textile material.

The rim 11 includes an outer wall 13 of generally sloping form and terminating in a thicker flat base edge 14, and an inner vertical wall 15

2

which depends downwardly as illustrated in Figs. 3 and 4 and is of less height than the height of the outer wall. In the illustrated embodiment, the walls are each rectangular, the outer wall 13 having sides 16, 17 and ends 18, 19, and the inner wall 15 having sides 20, 21 and ends 22, 23.

A frame 24, see Fig. 2, is formed integral with the rim 11, and includes horizontal sides 25, 26 which are joined to the contiguous vertical sides 20, 21 of the inner wall and have intermediate cut out portions 27, 28 for a purpose hereinafter described. The frame 24 has ends 29, 30 which are contiguous to but spaced from the inner wall ends 22, 23 to provide narrow spaces 31, 32, and 15 the inner wall ends have depending tabs 33, 34 extending to or slightly below the lower face of the frame 24. The inner wall sides 20, 21 have lateral projections 35, 36 positioned slightly above the frame sides to provide side channels 37, 38 therebetween, see Fig. 4, the cut out portions 27, 28 of the frame permitting the molding plungers for the lateral projections to move past the frame sides during the molding of the rim.

The article support or holder 12 is of a width 25 to slide into one space 31, and against the inner wall sides, and is flexible so that it may be slid over the frame sides and ends and through the channels 37, 38 so as to extend through the other space 32. Although this is ordinarily sufficient 30 to seat the article holder in the rim, it is preferred to provide the ends of the holder 12 with slots 39 for seating over the tabs 33, 34 to thus completely lock the holder 12 against relative movement with respect to the rim.

It is thus clear that the container includes 35 a one-piece rim, preferably of molded plastic, and an article holder of thin material, preferably cardboard, the two parts being readily assembled and locked together. A jewelry article is readily mounted on the holder by staples, cut-out tabs, or the like, and is distinctively displayed as if within a picture frame.

Although I have described one preferred constructional embodiment of the invention, it is 45 obvious that changes in the size, shape, and arrangement of the parts, and in the materials used, may be made to suit the requirements for different container designs, without departing from the spirit or the scope of the invention as defined in the appended claims.

I claim:

1. A shipping and display container having a rim with an upstanding ornamental outer wall and a depending vertical inner wall of less height 55 than the outer wall, said outer and inner walls

having sides and ends, a frame secured to the sides of the inner wall and having narrow sides contiguous the inner wall sides and narrow ends, at least one frame end being adjacent to and spaced from the contiguous inner wall end, and an article support element seating over the frame sides and engaging the inner wall sides and seating over the frame ends and beneath said contiguous inner wall end, the thickness of said support element being less than the space between the frame end and the contiguous wall end spaced therefrom.

2. A shipping and display container having a rim with an upstanding ornamental outer wall and a depending vertical inner wall of less height than the outer wall, said outer and inner walls having sides and ends, a frame secured to the sides of the inner wall and having narrow sides contiguous the inner wall sides and narrow ends, said frame ends being adjacent to and spaced from the contiguous inner wall ends, and an article support element seating over the frame sides and engaging the inner wall sides and seating over the frame ends and beneath the inner wall ends, the thickness of said support element being less than the space between the frame end and the contiguous wall end spaced therefrom, said inner wall sides having projecting parts extending over and in spaced relation to the frame sides to receive the support element therebetween.

3. A shipping and display container having a rim with an upstanding ornamental outer wall and a depending vertical inner wall of less height than the outer wall, said outer and inner walls having sides and ends, a frame secured to the sides of the inner wall and having narrow sides contiguous the inner wall sides and narrow ends,

5 said frame ends being adjacent to and spaced from the contiguous inner wall ends, and an article support element seating over the frame sides and engaging the inner wall sides and seating over the frame ends and beneath the inner wall ends, the thickness of said support element being less than the space between the frame end and the contiguous wall end spaced therefrom, said inner wall ends having tabs extending downwardly therefrom and said support element having slots adjacent its ends for lockingly seating over said tabs.

10 15 20 25 30 35 4. A shipping and display container having a rim with an upstanding ornamental outer wall and a depending vertical inner wall of less height than the outer wall, said outer and inner walls having sides and ends, a frame secured to the sides of the inner wall and having narrow sides contiguous the inner wall sides and narrow ends, said frame ends being adjacent to and spaced from the contiguous inner wall ends, and an article support element seating over the frame sides and engaging the inner wall sides and seating over the frame ends and beneath the inner wall ends, the thickness of said support element being less than the space between the frame end and the contiguous wall end spaced therefrom, said inner wall sides having projecting parts extending over and in spaced relation to the frame sides to receive the support element therebetween, said inner wall ends having tabs extending downwardly therefrom and said support element having slots adjacent its ends for lockingly seating over said tabs.

WILLIAM J. THOMPSON.
